ROTARY PUMP BLADE

James B. Brelsford and Jay M. Roth,
Dayton, Ohio

Application February 24, 1937, Serial No. 127,507

5 Claims. (Cl. 103—136)

(Granted under the act of March 3, 1883, as
amended April 30, 1928; 370 O. G. 757)

The invention described herein may be manufactured and used by or for the Government for governmental purposes, without the payment to us of any royalty thereon.

5 The present invention relates to improvements in rotary pumps and has for its object the provision of a rotary pump which is simple in construction, yet efficient in its operation.

In rotary pumps employing true circle inside housing bores, a relatively thick blade is necessary, involving undesirable increase in centrifugal forces during high speed operation. The aforesaid centrifugal forces may be greatly decreased by using one-piece thin blades, with both ends protruding from the rotor driving the same, but such construction involves ilmacon inside housing bores greatly increasing the manufacturing cost of such rotary pumps. It is a further desirable characteristic of thin blades that they slide more freely.

20 It is the particular object of our invention to permit retention of true circle inside housing bores and at the same time retain the thin blade advantages enumerated above.

25 With the foregoing and other objects in view, which will appear as the description proceeds, the invention consists of certain new and novel improvements in rotary pump blades, which will be hereinafter more fully illustrated in the accompanying drawings and more particularly pointed out in the appended claims.

30 Referring to the drawings, in which numerals of like character designate similar parts throughout the several claims:

35 Figure 1 is a cross-sectional view of a pump incorporating our invention.

Figure 2 is a cross-sectional view taken on the line 2—2 of Figure 1.

40 Figure 3 is a plan view of a pump incorporating our invention.

Figure 4 shows blade system development.

In Figures 1, 2, and 3, a pump assembly 1 is provided with a housing 2 and housing cover 3. Ingress and egress to the inner portion of the housing 2 is obtained through inlet-outlets 4a and 4b. During storage or shipment, the inlet-outlets 4a and 4b are closed by means of pipe plugs 5. As shown in Figure 2, the upper right hand extremity of the housing 2 is provided with an oil inlet 6, which during storage or shipment is sealed by a pipe plug 1. The housing cover 3 is similarly provided with an oil inlet 6 and pipe plug 7. As viewed in Figure 1, the housing 2 is provided with symmetrical housing cavities 8a and 8b, which are separated from one another by

means of a sleeve 9. The inner diameter of the sleeve 9 forms what is known to the art as the "inside housing bore" of the pump assembly. Ports 10a, 10b and 10c are cut through the sleeve 9 to provide communication with the housing cavities 8a and 8b.

5 Prior to installation within the sleeve 9, a rotor-blade element must be sub-assembled as follows: A rotor 11, provided with four equi-radially-spaced slots 12, is held with open end up to permit loose insertion of four blades 13 and a center pin 14. An end plate 18, provided with corresponding slots 12, is then secured to the open end of the rotor 11 by means of conventional counter-sunk machine screws. With completion of the above 10 operation, the housing 2 is next held with its open end uppermost to permit installation of the foregoing sub-assembly. It will be noted that the blades 13 are T-shaped at both inner extremities (bearing against the center pin 14) and outer extremities (bearing against the inner surface of the sleeve 11, referred to in the claims as "a cylinder"). Development of the former extremity will be dealt with in the description of Figure 3 which will hereafter be referred to as a base portion 15. The outer extremity of the blade 13 is provided with a rounded tip portion 16 and laterally overhanging portions 17 which fill in the space immediately without the periphery of the end plate 18 and corresponding end wall portion 20 of the rotor 1, the outer edges overhanging portions 17 coming into contact with the innermost surface of the housing 2 and the cover 3, respectively.

25 The rotor 11 is turned by means of a shaft 19 passing aft of a flange portion 21, provided upon the right hand extremity of the housing 2, Figures 2 and 3. The inner bore of the end plate 18 is provided with a filler-collar 20, fixed against rotation by means of a dowel pin 21. The filler-collar 20 acts as a bearing for a metering pin 22 fixed to the housing cover 3 by means of a cotter pin 23. An outer collar-like portion of the end plate 18 acts as an inner support for a ball bearing 24, recessed in the housing cover 3. A similar smaller ball bearing 25 is journaled upon the shaft 19 and finds outer support within a liner 26, recessed into the housing 2. As has been stated before, a mounting flange 27 is provided 30 for installation of the pump assembly 1 upon an appropriate motor device. An oil duct 28 is provided for lubrication of the ball bearing 24, while a second oil duct 29 provides the ball bearing 25 with lubrication. Intercommunication between 35

oil ducts 28 and 29 is provided by a third oil duct 30.

Figure 4 shows in diagrammatic form the evolution of the relatively thick blade universally employed in rotary pumps. The inner diameter of the sleeve 9 is represented by a circle 31, through the center of which are passed horizontal axis X—X and vertical axis Z—Z. The point of common intersection of the aforesaid axes is designated by the letter A. The outer diameter of the center pin 11 is represented by a circle 32, which also has the axes X—X and Z—Z passing through the center thereof. The outer diameter of the rotor 11 is represented by a circle 33, which 5 "contacts" the circle 31 at the point of intersection of the vertical axis Z—Z and the latter circle. While the vertical axis Z—Z passes through the center of the circle 33, the horizontal axis Y—Y passing therethrough is separated from, though 10 parallel to, the axis X—X for the reason that the spacing of these two axes represents the eccentricity of the rotor 12 with respect to the inner surface of the sleeve 9. Common intersection of the axes Y—Y and Z—Z are indicated by the 15 letter B. An arc 34 is first inscribed to the left of the vertical axis Z—Z in such a manner that all points thereon will be equi-distant, radially, from the circles 31 and 32. The point of intersection of the arc 34 and the axis Y—Y has been designated by the letter C. It is now apparent that 20 construction of radial line A—D, through the point C, will determine the point of tangencies of the arcs 36 and 37 next struck about the common center C. Thus, to develop the minimum 25 width of blade suitable for the eccentricity shown in Figure 4, it is necessary only that two horizontal lines 37 and 38 be passed, respectively, through the points of tangency of the arcs 35 and 36, respectively, with the circles 31 and 32. If the 30 rotor represented by the circle 33 be provided with four equally spaced slots of a width sufficient to engage the sliding sides of four blades bounded by the line 37, the line 38, and those portions of the arcs 35 and 36 lying therebetween, it is at 35 once apparent that the center pin 21 will always be held in the central position indicated in Figure 1. However, due to excessive thickness and attendant overweight, the blades hereinabove developed will be subject to the serious drawbacks 40 already discussed under the objects of our invention.

The novelty in our invention consists of selecting at random a point F in relatively close proximity to the circle 31, Figure 4. This point we have 45 further located on the horizontal axis Y—Y, of the rotor 12. If a straight line A—E be erected through the point F, it is at once apparent that its intersection with circles 31 and 32 represents the 50 points of tangency of the arcs 39 and 40, having their common center at the point F. If parallel 55 lines 41 and 42 be erected equi-distantly from the horizontal axis Y—Y, such that the right hand extremity of the line 42 passes through the point of tangency of the circle 31 and the arc 39, the maximum required width of the outer portion of 60 our new and improved rotor pump blade will be indicated. The inner portion of the same blade is determined by erecting parallel and equi-distantly spaced lines 43 and 44, about the axis Y—Y, 65 such that the inner portion of the line 43 passes through the point of tangency of the circle 32 and the arc 40. It is thus assured that the inner bearing surface of the base portion 15 will always so 70 contact the outer surface of the center pin 14 that 75 the point F is never permitted to move inwardly

away from the inner surface of the sleeve 9, represented by the circle 31. There is thus no mechanical divergency between blade positioning, with respect to inner and outer tangencies with the circles 31 and 32, in either embodiment of the 5 diagrammatic forms of blade shown in Figure 4.

Those skilled in the art are familiar with that 10 system of rotor-blade element in which the sides 41 and 42 of the right hand blade of Figure 4 are extended completely across the rotor represented by the circle 33. The single thin blade resulting 15 is substantially counterbalanced against centrifugal forces, eliminates necessity of the center pin 14, and has in addition the freely sliding characteristic enumerated above. With the horizontal 20 axis Y—Y turned into coincidence with the vertical axis Z—Z of Figure 4, the over-all length of the single thin blade is substantially equal to the diameter of the circle 31. As the blade turns into coincidence with the horizontal axis Y—Y, the 25 outer extremities thereof are gradually and equally projected beyond the limits of the circle 31 such that their path takes the form of a limacon curve. It is at once apparent that the cost of manufacturing an "inside housing bore" of irregular curve form seriously increases the total pump cost.

Rotary pumps equipped with our improved 30 blades operate in a manner identical to the operation of conventional rotary pumps with the thick 35 blade section of Figure 4. The novelty in our invention resides in reducing centrifugal forces through marked reduction in blade mass and through further improving the free sliding characteristics of the blades. 35

Although the description is specific to the illustrations in the drawings, it is to be understood that there may be numerous departures therefrom which will still be within the field and scope of the invention, so that we do not wish to be restricted 40 thereto, but only in so far as the appended claims are so limited.

What we claim as new is:

1. A rotary pump comprising a housing having 45 a true circle inside bore, a member having a centralizing cylindrical surface disposed within said bore, a cylindrical rotor member mounted eccentrically in said bore to contact the wall thereof and surround said centralizing surface, said rotor being provided with a radial slot, a one-piece 50 blade in said rotor slot resting between the wall of said housing bore and said centralizing surface and having convex arcuate end bearing surfaces, said blade having both of its arcuate end bearing surfaces struck from a common center, the radius 55 of curvature of the bore bearing end being less than the radius of curvature of the centralizing surface bearing end, the points of tangency of said convex bearing surfaces being coincident with a radial line passing through the longitudinal axis 60 of the aforesaid housing bore and the common center of the convex surface radii, and means for establishing ingress-egress communication with said housing bore on opposite sides of the contact between said cylindrical rotor member and said 65 housing bore.

2. A rotary pump comprising a housing having 70 a true circle inside bore, a member having a centralizing cylindrical surface disposed within said bore, a cylindrical rotor member mounted eccentrically in said bore to contact the wall thereof and surround said centralizing surface, said rotor being provided with a radial slot, a one-piece 75 blade in said rotor slot resting between the wall of said housing bore and said centralizing surface 75

and having convex arcuate end bearing surfaces, said blade having both of its arcuate end bearing surfaces struck from a common center, the radius of curvature of the bore bearing end being less than the radius of curvature of the centralizing surface bearing end, the points of tangency of said convex bearing surfaces being coincident with a radial line passing through the longitudinal axis of the aforesaid housing bore and the common center of the convex surface radii, the thickness of the blade throughout the length of the rotor slot bearing portion thereof being substantially equal to the cord of the bearing portion of the bore bearing end of said blade and means for establishing ingress-egress communications with said housing bore on opposite sides of the contact between said cylindrical rotor member and said housing bore.

3. A rotary pump comprising a housing having a true circle inside bore, a member having a centralizing cylindrical surface disposed within said bore, a cylindrical rotor member mounted eccentrically in said bore to contact the wall thereof and surround said centralizing surface, said rotor being provided with not less than three equally spaced radial slots, a like number of one-piece blades in said rotor slots resting between the wall of said housing bore and said centralizing surface and having convex arcuate end bearing surfaces, 10 said blades having both of their arcute end bearing surfaces struck from a common center, the radii of curvature of the bore bearing ends of said blades being less than the radii of curvature of the centralizing surface bearing ends of said blades, 15 the points of tangency of each pair of convex bearing surfaces being coincident with a radial line passing through the longitudinal axis of the aforesaid housing bore and the common center of each pair of convex surface radii, and means for establishing ingress-egress communication with said housing bore on opposite sides of the contact between said cylindrical rotor member and said housing bore.

20 4. A rotary pump comprising a housing having a true circle inside bore, a cylindrical center pin freely floatingly disposed within said bore, a cylindrical rotor member mounted eccentrically in said bore to contact the wall thereof and surround said center pin, said rotor being provided with not less than three equally spaced radial slots, a like number of one-piece blades in said rotor slots resting between the walls of said housing bore and said center pin and having convex arcuate end bearing surfaces, said blades having both of their 25 arcuate end bearing surfaces struck from a common center, the radii of curvature of the bore bearing ends of said blades being less than the radii of curvature of the center pin bearing ends of said blades, the points of tangency of each pair of convex bearing surfaces being coincident with a radial line passing through the longitudinal axis of the aforesaid housing bore and the common center of each pair of convex surface radii, and means for establishing ingress-egress communication with said housing bore on opposite sides of the contact between said cylindrical rotor member and said housing bore.

25 5. A rotary pump comprising a housing having a true circle inside bore, a cylindrical center pin freely floatingly disposed within said bore, a cylindrical rotor member mounted eccentrically in said bore to contact the wall thereof and surround said center pin, said rotor being provided with not less than three equally spaced radial slots, a like number of one-piece blades in said rotor slots resting between the walls of said housing bore and said center pin and having convex arcuate end bearing surfaces, said blades having both of their 30 arcuate end bearing surfaces struck from a common center, the radii of curvature of the bore bearing ends of said blades being less than the radii of curvature of the center pin bearing ends of said blades, the points of tangency of each pair of convex bearing surfaces being coincident with a radial line passing through the longitudinal axis of the aforesaid housing bore and the common center of each pair of convex surface radii, and means for establishing ingress-egress communication with said housing bore on opposite sides of the contact between said cylindrical rotor member and said housing bore.

35 6. A rotary pump comprising a housing having a true circle inside bore, a cylindrical center pin freely floatingly disposed within said bore, a cylindrical rotor member mounted eccentrically in said bore to contact the wall thereof and surround said center pin, said rotor being provided with not less than three equally spaced radial slots, a like number of one-piece blades in said rotor slots resting between the walls of said housing bore and said center pin and having convex arcuate end bearing surfaces, said blades having both of their 40 arcuate end bearing surfaces struck from a common center, the radii of curvature of the bore bearing ends of said blades being less than the radii of curvature of the center pin bearing ends of said blades, the points of tangency of each pair of convex bearing surfaces being coincident with a radial line passing through the longitudinal axis of the aforesaid housing bore and the common center of each pair of convex surface radii, and means for establishing ingress-egress communication with said housing bore on opposite sides of the contact between said cylindrical rotor member and said housing bore.
